UNITED STATES PATENT OFFICE

JEREMIAH A. SULLIVAN, OF BROOKLYN, NEW YORK

IGNITION SWITCH

Application filed February 7, 1928. Serial No. 252,473.

This invention relates to ignition systems for automobiles and more particularly to means for breaking the ignition circuit to prevent unauthorized use of the automobile. While suitable ignition locks are usually provided on automotive vehicles, it quite frequently occurs that the owner or driver of the vehicle will leave the vehicle and permit the engine to remain running, or, if he breaks the ignition circuit by turning the key which locks the switch in open position, he perhaps leaves the key in the lock. Not infrequently duplicate keys are employed to unlock the ignition switch and the vehicle stolen. It is the purpose of the present invention to provide a device operable by the opening of the vehicle side door adjacent the driver which automatically breaks the ignition circuit when the door is opened. It is also an object of the invention to employ a novel form of switch designed to be opened by the vehicle door but which can be closed only by the actuation of a combination or permutation switch operating mechanism. Further objects will be apparent from the following description taken in connection with the accompanying drawings, in which:

Fig. 1 is a sectional elevation of the switch and its opening and closing mechanism;

Fig. 2 is a sectional plan view taken on the line 2—2 of Fig. 1;

Fig. 3 is a sectional plan view taken on the line 3—3 of Fig. 1; and

Fig. 4 is a view of the switch knob and dial.

Referring to the drawings, the switch is housed in a casing 11 attached to the dash 12 of the vehicle. The switch comprises an operating shaft 13 projecting through the dash and having secured thereto in a manner to be described hereinafter the switch arms 14, 15, 16 and 17. On the projecting end of the shaft, that is, on that side of the dash exposed to the view of the driver, is secured a knob and pointer 18 adapted to move over a graduated dial 18'. Also secured to the operating shaft is a toothed wheel or ratchet 19.

Referring to Fig. 2, it will be seen that the arms 14, 15 and 16 each have a pin and slot connection with the operating shaft 13, a disk 20 being rigidly secured to the shaft and

having four pairs of pins 21 projecting therefrom at suitably spaced intervals. Each pair of pins is adapted to cooperate with arcuate slots 22 in a base portion 23 at the inner end of the arm, the slots varying in length for each arm. Each arm is curved intermediate its ends, as at 24, and its outer end is parallel, but in a different plane, with the inner end of the arm. The outer portion of the arm is provided with a projection 25 which may be pressed in the arm.

The ignition circuit includes a number of segmental conductors 26, each spaced a slight amount from the next, and all mounted on a circular plate 27 secured to casing 11 by screws or other suitable fastenings 28. The end segments are connected to binding terminals 29 on the plate 27, these terminals also being connected to the spark plugs and source of electric current. The arms 14, 15, 16 and 17 may be positioned, by proper manipulation of the switch, to bridge the gaps between the ends of adjacent segments and thus close the circuit.

Pivoted to a bracket 30 on the dash is a bell-crank lever 31 one arm of which is connected to a rack 32 slidably mounted in the casing 11. The other arm of the bell-crank lever is connected to a rod 33 slidably secured to the side of the vehicle and adapted to be engaged by a lug 34 on the vehicle door 35. A coil spring 36 is interposed between a collar 37 on the rack 32 and a projection 38 of the casing and surrounds the rack while a light leaf spring 39 presses the rack toward the ratchet, the latter being in two parts and pivoted at 40. It will be noted that the teeth on the rack each have a straight face and an inclined face so that the rack is adapted to slide over the ratchet when moving in one direction but engages the ratchet when moving in the opposite direction. When the vehicle door is closed the spring 36 is compressed, thus placing the rack 32 in the dotted position clear of the gear 19.

From the foregoing description the operation will be apparent. Normally, that is when the vehicle door 35 is closed and all of the segments bridged by the switch arms, the ignition circuit is closed. Should the oper-

ator of the car leave it for any reason the door must be opened, whereupon the spring 36 moves the teeth of the rack into engagement with the ratchet and turns the shaft 13 carrying the switch arms. The ignition circuit is thus automatically broken. To reset the switch to close the circuit, it is necessary to turn the resetting knob alternately in opposite directions to again bridge the segments 10 26. This can be done only by moving the arms through a predetermined arc in each direction, the pin and slot connections between the shaft and arms varying for each arm. It will be apparent, for instance, that if 15 the arms are moved counterclockwise a predetermined amount the arm 14 will bridge two of the segments but the other arms will be carried past the other gaps. Reversing the movement of the arms the arm 15 will be 20 brought to bridging position. The operation is continued until all of the arms are in proper position.

As shown in Fig. 2 the arcuate slots 22 vary in length for each arm. When the projection 25 on arm 14 engages the gap between its adjacent segments, this position being determined by the pointer 18 and the dial 18', the knob is turned in the opposite direction a distance less than the length of the slots 30 in arm 14 to bring arm 15 into bridging position. There is, therefore, no relative movement between the arm 14 and the segments. Since the slots are progressively shorter each 35 arm may be moved relative to the other until all of the projections 25 engage the gaps between the segments. The rack is so designed to move the ratchet wheel through a distance greater than the length of any of the slots so that all of the arms are disengaged from the gaps.

While a specific embodiment of the invention has been described and illustrated, it is obvious that other means may be employed to operate the switch and it is not intended that 45 the invention be limited to the details illustrated in the accompanying drawings.

I claim:

1. A door operated switch for an electric 50 circuit comprising a plurality of contact members for closing the circuit, means for separating said members to open the circuit when the door is being moved from closed to open position, said means being incapable of opening the circuit during door closing operation, and means for resetting the switch to closed position when the door is either fully opened or fully closed.

2. A door operated switch for an electric 60 circuit comprising a plurality of contact members for closing the circuit, ratchet means for separating said members to open the circuit, a rack for actuating said ratchet, spring means for moving said rack in a direction to separate said members when the 65 door is moved from closed to open position,

said spring means being contracted when the door is closed, said rack being incapable of opening the circuit during door closing operation, and means independent of said rack and door for resetting the switch to closed position when the door is either fully opened or fully closed.

In testimony whereof, I have signed my name to this specification this 4th day of February, 1928.

JEREMIAH A. SULLIVAN.
